PLUMB BOB

Joseph Prutch, 317 Sepulveda St., San Pedro, Calif.

Filed May 3, 1963, Ser. No. 74,731

Term of patent 14 years

(Cl. D52—1)

I claim:

The ornamental design for a plumb bob, as shown.
